UNITED STATES PATENT OFFICE.

CHESTER L. WRIGHT, MASON L. SMART, AND CALVIN M. HOPPER, OF SUMNER,
MISSOURI.

AUTOMATIC MAIL-POUCH-LOCKING APPLIANCE.

1,162,121.

Specification of Letters Patent. Patented Nov. 30, 1915.

Application filed July 3, 1914. Serial No. 848,834.

To all whom it may concern:

Be it known that we, CHESTER L. WRIGHT, MASON L. SMART, and CALVIN M. HOPPER, citizens of the United States, residing at 5 Sumner, in the county of Chariton and State of Missouri, have invented certain new and useful Improvements in Automatic Mail-Pouch-Locking Appliances; and we do hereby declare the following to be a full, clear, 10 and exact description of the invention, such as will enable others skilled in the art to which it appertains to make and use the same.

This invention relates to locks and particularly to locks for mail pouches.

Heretofore the custom has been to lock mail pouches with an ordinary pad lock which is an intricate process causing a waste of time and energy, trouble that is obviated 20 in this invention.

One of the objects of this invention is to give a device that is automatic in its operation of locking the mail pouch as well as being easy of manipulation.

Another object of this invention is to give a device that is strong, durable and easy to manufacture, having comparatively few parts.

Similar reference characters refer to similar parts throughout the specification and drawings, in which,

Figure 1 is a sectional view of the device in locked position. Fig. 2 a sectional view of the device in unlocked position. Fig. 3 a 35 face view of the interior key plate. Fig. 4 a detail of one of the checking tumblers. Fig. 5 a view of a preferred form of key.

1 is the plate forming one wall of the lock having a slot 2 suitable for the insertion of a 40 staple or link 3 connected to a mail pouch or other suitable object. A locking bolt 4 having a right angle portion 5 is pivotally mounted upon the lug 6, said bolt having a suitable eye 7 for this purpose. The rear 45 edge 8 of the locking bolt has a suitable notch or recess 9 in which is seated a locking tumbler or latch 10. This latch 10 is pivotally mounted upon the lug 11 having a suitable eye 12 for this purpose. A second tumbler 13 is pivotally mounted upon the lug 14, said tumbler having a suitable eye 15 for this purpose and operates to lock the locking bolt 4 by means of a hook member 15' which engages a suitable shoulder or projection 16

extending from one end of the locking bolt 55 4. At the opposite side of the tumbler 13 is a second projection 17 which operates against the surface 18 to throw the locking bolt into unlocked position upon the operation of the device. A spring 19 retains the 60 tumblers into operative position against the locking bolt, the portion 20 lying against the tumbler 10 and the portion 21 lying against the tumbler 13 for this purpose.

The locking bolt 4 when in locked position 65 abuts against the lug 22 and prevents said locking bolt from playing too far. A lever or trip 23 is pivotally mounted upon the lug 24 by means of a suitable eye 25 in said trip and is normally retained in a lowered position by a spring 26 which is mounted on the member 27 and abuts against the surface 28 of the trip 23. A projection 29 retains the spring from slipping off the trip while a projection 30 retains the 70 spring from slipping off the member 27, this member 27 being mounted to the plate 1 by means of a bolt or rivet 31. A projection 32 depends from the middle portion of the trip in such manner as to hit the lug or stay 75 22 thereby preventing the trip from lowering too far under the pressure of the spring as is plainly indicated in Fig. 2 of the drawing. The inner faces 33 and 34 of the tumblers 10 and 13 respectively are spaced a predetermined distance apart, said surfaces 33 and 34 being operated upon by the prongs of the key 35. A multiplicity of tumblers 36 are mounted upon the lug 14 by means of suitable eyes 37, each of these tumblers having a hook portion 38 adapted to operate against the shoulder 16 of the locking bolt. The surfaces 39 of each of the tumblers 36 are placed at a different or predetermined position within reach of prongs 40 of the 85 key 35, these prongs being of a different length than of the prong 41 which operates the tumblers 10 and 13. These tumblers 36 are for the purpose of acting as a check or lock against the locking bolt 4 in case of unlawful attempt to operate the lock by means of a key not suited for this purpose.

A key plate 42 is mounted upon the lugs 11 and 14 by means of suitable eyes 43 and 44 and has in the center thereof a slot key 105 hole 45 to allow the insertion of the key to reach the tumblers. If it is desired the auxiliary tumblers 36 and the plate 42 can

be dispensed with and any make of key suitable for pressing apart the tumblers 10 and 13 can be used.

In operation a key having suitable prongs 5 is inserted through the key hole until the end 46 abuts against its seat 47 and then is given a 90° turn. In turning it the tumblers 36 are first operated upon because their surfaces 39 are nearer than the surfaces 33 and 34 of the tumblers 10 and 13, these tumblers 36 being thereby thrown out of engagement with the locking bolt. Next the tumblers 10 and 13 are spread, this action releasing the locking bolt of the tumbler 10 at 9 and the 10 hook 15' at 16 and the locking bolt is thrown by means of the hook 17 coming in contact with the surface 18, thereby throwing the tumbler lock over into the position as shown in Fig. 2. This action allows the 15 staple 3 to be withdrawn, thereby causing the trip 23 to drop as far as it is allowed to go which action causes the surface 48 to come in contact with the surface 50 of the locking bolt thereby retaining it in unlocked position until another staple is inserted 20 which throws back the trip 23 and allows the locking bolt and its operating members to respond into locked position, the trip 23 having a rounded surface 49 to facilitate 25 this operation.

Although we have described the preferred embodiment of our invention, we reserve and may exercise the right to make such changes in the construction, combination and arrangement of parts thereof as do not depart 35 from the spirit of the invention and the scope of the appended claims.

Having thus fully described our invention, what we claim as new and desire to 40 secure by Letters-Patent of the United States is:

1. An automatic lock comprising a pivoted locking bolt having a notch in one edge thereof, an angular extension at its upper 45 end, a projection at its opposite end, a spring pressed locking tumbler adapted to engage said notch and hold the bolt in locked position, a plurality of tumblers, each having a hook adapted to engage and 50 interlock with the projection of the locking bolt, a projection on one of said latter tum-

blers adapted to engage the face of the locking bolt to move the locking bolt to open position, and a trip having an extension adapted to move in the path of the angular 55 end of the locking bolt to hold the locking bolt in unlocked position.

2. An automatic lock comprising pivoted tumblers, a pivot locking bolt retained in a locking position by said pivoted tumblers, a 60 pivoted trip having a check extension thereto, and means to check undue play of said locking bolt and said trip.

3. An automatic lock comprising a locking bolt having an angular extension at one 65 end, and a notch in one edge thereof, a pivoted locking tumbler adapted to engage said notch and hold the bolt in locked position, a plurality of tumblers having hooks thereon adapted to engage parts of the locking bolt 70 and interlock therewith, one of said latter tumblers having a projection adapted to engage the locking bolt and move the same to unlocked position, a pivoted trip having an extension at one end adapted to move into 75 the path of the locking bolt and hold the same in unlocked position, means to limit the travel of said trip, and a spring adapted to direct pressure against one end of the trip to move the opposite end thereof into 80 the path of the locking bolt.

4. An automatic lock comprising a pivotally mounted locking bolt, a pivotally mounted trip abutting against said locking bolt and normally retaining the same in unlocked position, a pivoted tumbler one end of which is normally seated against said locking bolt to retain the same in locked position, a second pivoted tumbler operating to throw the locking bolt, and means to release said locking bolt to allow it to move to locking position.

In testimony whereof we have signed our names to this specification in the presence of two subscribing witnesses.
